UNITED STATES PATENT OFFICE

HENRY S. YOUNG, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SIGNALING SYSTEM

Application filed May 17, 1929. Serial No. 363,807.

My invention relates to railway signaling systems of the type involving signals controlled by track circuits.

One feature of my invention is the provision of means for preventing an undesirable momentary operation of a signal when a light engine or a car passes at high speed from one track section to another if the track relay for the rear section closes before the track relay for the forward section opens.

I will describe two forms of signaling systems embodying my invention, and will then point out the novel features thereof in claims.

In the accompanying drawing, Fig. 1 is a diagrammatic view showing one form of signaling system embodying my invention. Fig. 2 is a fragmentary view showing a modification of a portion of the signaling system shown in Fig. 1 and also embodying my invention.

Similar reference characters refer to similar parts in each of the views.

Referring first to Fig. 1, the reference characters 1 and 1^a designate the track rails of a railway track along which traffic normally moves in the direction indicated by the arrow. These rails are divided by insulated joints 2 to form a plurality of blocks of which only one block A—B is shown in the drawing. This block is further divided by insulated joints 2 to form two track sections A—X and X—B. Each of these track sections is provided with a track circuit comprising a track battery 3 connected across the rails at one end of the section and a track relay T connected across the rails at the other end of the section.

Located adjacent the entrance end of the block A—B is a light signal S^A, which signal, as here shown, is of what is known as the "searchlight" type. This signal comprises a member 5 mounted to oscillate and controlled by two windings 6 and 7. The member 5 carries three roundels 4^G, 4^R and 4^Y, arranged to co-operate with an electric lamp 21 in such manner that when the member 5 is in its middle position, to which it is biased, roundel 4^R is in front of the lamp 21; whereas, when the member 5 is swung to the left or to the right, from this middle position, roundel

4^Y or roundel 4^G is placed in front of the lamp 21. As shown in the drawing, the lamp 21 is above the roundels, but it is placed in this location solely for purposes of illustration, and in actual practice it is understood that this lamp is located directly behind the roundels. The signal indicates "stop", "caution" or "proceed", according as the roundel 4^R, 4^Y or 4^G is located in front of the lamp 21. Operatively connected with the member 5 are two contacts 9 and 10, which contacts are operated in such manner that when the signal indicates stop, both of the contacts are in their lower positions, when the signal indicates caution contact 9 is down and contact 10 is up, whereas, when the signal indicates proceed, contact 9 is up and contact 10 is down. A signal of the type thus described is disclosed and claimed in Reissue Letters Patent of the United States No. 14,940, granted to E. J. Blake on August 31, 1920.

Associated with the signal S^A is an auxiliary relay C, a slow releasing relay D^A, and a thermostat T. The thermostat T comprises a heating winding 19 and a normally open contact 17—18 which becomes closed after the heating winding has been supplied with current for a given short interval of time.

The operating winding 6 of signal S^A is provided with a circuit which is controlled by both the track relays T^A and T^B, as well as by a slow releasing relay D^B located at point B and corresponding to relay D^A at point A. This circuit also includes the auxiliary relay C. When relay D^B is energized, the circuit is as follows: from battery E at location B, through the front point of contact 13 of relay D^B, contact 12 of track relay T^B, contact 12 of track relay T^A, winding of relay C, signal operating winding 6, contact 11 of track relay T^A, contact 11 of track relay T^B, and the front point of contact 14 of relay D^B to battery E. When relay D^B is de-energized, the circuit is the same as before, except that the polarity of the current supplied to winding 6 is reversed, due to the pole-changing action of contacts 13 and 14 of relay D^B.

Under normal conditions, that is, when signal S^A indicates proceed, relay D^A is energized by a circuit which includes signal

contact 9, so that winding 7 of signal S^A is energized, the circuit for winding 7 being from terminal B of a suitable source of current, through contact 16 of relay D^A and 5 signal operating winding 7 to terminal O of the same source of current.

I will assume that signal S^A indicates proceed, as shown in the drawing, and that a vehicle moving toward the right passes this 10 signal. As the vehicle enters section A—X it causes track relay T^A to open, thereby opening the circuit for signal winding 6, so that signal S^A moves to the stop position. The reversal of the position of contact 9 opens 15 the circuit for relay D^A , so that the circuit for signal winding 7 becomes open at contact 16 of this relay. As the vehicle passes from section A—X to section X—B, no change 20 will occur because the circuit for signal winding 6 will remain open at the contacts of track relay T^B . As the vehicle passes out of block A—B, the circuit for winding 6 of signal S^A will become closed, and current of 25 reverse polarity will be supplied to this circuit because relay D^B will be opened due to the vehicle entering the block next to the right. The energizing of relay C closes a circuit for the heating winding 19 of thermostat T, which circuit is from terminal B, 30 through winding 19, contact 15 of relay C, and contacts 10 and 9 of signal S^A (both of which will be down) to terminal O. After the lapse of a short time interval, contact 35 17—18 of thermostat T will close, whereupon, winding 7 of signal S^A will become energized through a temporary circuit which passes from terminal B, through contact 17—18 of thermostat T and signal winding 7 to terminal O. Signal S^A will then move to the caution 40 position, wherein contact 10 will be moved to its upper position. Relay D^A will then become energized through a circuit which passes from terminal B, through contact 10 in the upper position and contact 9 45 in the lowered position to terminal O. The normal circuit for winding 7 will then be closed, through contact 16 of relay D^A . As soon as signal S^A moves to the caution position, the circuit for the heating winding 19 of thermostat T will become open at contact 50 10, so that this winding will be de-energized and the contact of the thermostat will again open. When the vehicle passes out of the block to the right of point B, relay D^B will 55 become energized, so that current of normal polarity will be supplied to winding 6 of signal S^A , with the result that this signal will move to the proceed position. Relay D^A will still be energized by virtue of a circuit 60 which includes contact 9 in its upper position, so that the circuit for winding 7 through contact 16 of this relay will remain closed. Because of its slow releasing characteristic, relay D^A will not open during the reversal 65 of contacts 9 and 10.

I will now assume that while the vehicle is passing from section A—X to section X—B, the contacts of track relay T^A close before the contacts of track relay T^B open, so that for a short interval of time the circuit for winding 6 of signal S^A is closed. If winding 7 were constantly energized, this momentary energization of winding 6 might cause a quick-acting signal, such as a searchlight signal, to give a momentary proceed or caution indication depending on whether relay D^B is energized or de-energized. With apparatus embodying my invention, however, this momentary proceed or caution indication is prevented, because the thermostat T prevents winding 7 from becoming energized during the short interval in which the contacts of both track relays T^A and T^B may be closed.

When the vehicle passes point B, track relay T^B will close before relay D^B opens, because of the slow releasing characteristic of the latter relay, but signal S^A will not give a momentary proceed indication because thermostat T will delay the energization of signal winding 7 until after relay D^B has opened.

Referring now to Fig. 2, the apparatus shown in this view is the same as that shown in Fig. 1, except that the auxiliary relay C is connected in multiple with signal winding 6, and a back contact 20 of relay D^A is included in the branch circuit for relay C to de-energize this relay after signal S^A has been moved to the caution or proceed position.

Although I have herein shown and described only two forms of signaling systems embodying my invention, it is understood that various changes and modifications may be made therein within the scope of the appended claims without departing from the spirit and scope of my invention.

Having thus described my invention, what I claim is:

1. In combination, two successive sections of railway track; a track circuit including a track relay for each section, a signal for said sections having two co-operating windings, a circuit for the first of said windings controlled by both of said track relays and including an auxiliary relay, a thermostat having a heating winding and a normally open contact, a circuit for said heating winding including a front contact of said auxiliary relay and contacts closed only when said signal indicates stop, a circuit for the second of said signal windings including the contact of said thermostat, a slow releasing relay having a circuit which includes a contact closed only when said signal gives a proceed indication, and an auxiliary circuit for said second signal winding including a front contact of said slow releasing relay.

2. In combination, two successive sections of railway track, a track circuit including a

track relay for each section, a signal for said sections having two co-operating windings, a circuit for the first of said windings controlled by both of said track relays and including an auxiliary relay connected in series with said first winding, a thermostat having a heating winding and a normally open contact, a circuit for said heating winding including a front contact of said auxiliary relay and contacts closed only when said signal indicates stop, a circuit for the second of said signal windings including the contact of said thermostat, a slow-releasing relay having a circuit which includes a contact closed only when said signal gives a proceed indication, and an auxiliary circuit for said second signal winding including a front contact of said slow releasing relay.

3. In combination, two successive sections of railway track, a track circuit including a track relay for each section, a signal for said sections having two co-operating windings and requiring that both windings be energized in order that the signal may give a proceed indication, a circuit for the first of said windings controlled by both of said track relays and including the winding of an auxiliary relay, and slow acting means for energizing the second of said signal windings after said auxiliary relay has been closed for a given interval of time.

4. In combination, two successive sections of railway track, a track circuit including a track relay for each section, a signal for said sections having two co-operating windings and requiring that both windings be energized in order that the signal may give a proceed indication, a circuit for the first of said windings controlled by both of said track relays, and means including a slow acting device for energizing the second of said signal windings after current has been supplied to the circuit for the first winding for a given interval of time.

5. In combination, two successive sections of railway track, a track circuit including a track relay for each section, a signal for said sections having two co-operating windings and requiring that both windings be energized in order that the signal may give a proceed indication, a circuit for the first of said windings controlled by both of said track relays and including the winding of an auxiliary relay, means including a slow-acting device for energizing the second of said signal windings after said auxiliary relay has been closed for a given interval of time provided the signal indicates stop, and other means for keeping said second signal winding energized independently of said slow acting device while the signal gives a proceed indication.

6. In combination, two successive sections of railway track, a track circuit including a track relay for each section, a signal for said

sections having two co-operating windings and requiring that both windings be energized in order that the signal may give a proceed indication, a circuit for the first of said windings controlled by both of said track relays and including the winding of an auxiliary relay, means including a slow acting device for energizing the second of said signal windings after said auxiliary relay has been closed for a given interval of time provided the signal indicates stop, and other means for keeping said second signal winding energized independently of said slow acting device while the signal is changing from one proceed indication to another as well as while it is giving a proceed indication.

In testimony whereof I affix my signature.
HENRY S. YOUNG.
